UNITED STATES PATENT OFFICE.

CHARLES W. DAKE, OF CHICAGO, ILLINOIS, ASSIGNOR TO THE PYLE-NATIONAL COMPANY, OF CHICAGO, ILLINOIS, A CORPORATION OF NEW JERSEY.

VALVE.

Application filed September 2, 1920. Serial No. 407,620.

To all whom it may concern:

Be it known that I, CHARLES W. DAKE, a citizen of the United States, residing at Chicago, in the county of Cook and State 5 of Illinois, have invented a certain new and useful Improvement in Valves, of which the following is a specification.

This invention relates to a steam valve and particularly to a valve of the type 10 which is adaptable for use with a steam turbine or motor generator set. One of the objects of this invention is to produce a valve which is more nearly balanced than is generally the case with valves of this type. 15 Other objects will appear from time to time throughout the specification and claims.

The invention is illustrated in the accompanying drawings, wherein—

Fig. 1 illustrates the valve as positioned 20 in a steam turbine. The associated parts are diagrammatically illustrated only so far as necessary;

Fig. 2 is a horizontal section along the line 2—2 of Fig. 1.

Like parts are described by like characters throughout.

A is a valve casing having the central bore A'. The two inlet ports A² A² and the two outlet ports A³ A³ which are in 30 communication with the annular groove A⁴ about the valve casing. From these outlet ports steam is discharged through the port A⁶ toward the nozzle of the turbine. B is a bushing in the lower and narrower part of 35 the valve casing, and is relatively long to give a long bearing for the valve operating stem C and therefore diminishes the escape of steam. The bushing B is provided with an inclined upper surface B' and is 40 smaller than the cavity within which it rests. Thus it furnishes means whereby any sediment in the steam can be carried away from the valve stem and deposited in the pocket about it so as to minimize 45 the danger of sticking of the valve operating stem. C' is the valve piston set within the valve casing and provided with the annular grooves C² C² by means of which a water packing is established. C³ is a perforation 50 in the part C' through which steam may pass. C⁴ is an extension from the valve piston and is provided with the lateral enlargement C⁵ against which the spring D bears. E is a cap or plug enclosing the 55 spring D and the upper end of the valve

stem C⁴. It is adapted to be screwed in the valve casing and to compress the spring in order to adjust the setting of the valve. The valve stem C⁴ is made of sufficient length that when the valve is properly adjusted, 60 its upper end may be even with the upper surface of the cap E which is perforated and through which the valve stem is adapted to penetrate. The valve assembly is fitted in place in the turbine and is there secured 65 by means of the plug F. The plug F encloses a spring G which is secured within it and bears upon the top of the cap E, thus controlling the cap or plug so as to hold the valve parts in a spring secured relation. 70 H is a lever in contact with the lower end of the valve operating stem. The lever H is connected with a governor not here shown, the details of which form no part of this invention. The valve is operated in response to the governor which causes the lever H to rise and thus move the valve upward and cuts off the discharge port of the valve, and thus either limits or entirely cuts 75 off the steam supply. 80

The valve stem C⁴ which as above suggested is normally flush with the top of the cap E, furnishes a very satisfactory index whereby the operator can tell when the valve inside the casing is properly adjusted, that is when 85 its valve stem is flush, the valve is in the proper place, and is of course held in that place against the pressure of the spring D by the governor. For the purpose of illustrating this feature, I have applied a very 90 diagrammatic governor adjustment, the idea being that the rock shaft K is rotated by the governor, and it has keyed thereon a quadrant K', slotted as at K². The arm H is rotatably mounted on the shaft K and is 95 adapted to be locked to the quadrant K² by means of a hand screw and wheel K³.

When the operator is going to adjust the valve so that the governor will hold it at an open position for normal running, he 100 will release the hand wheel K³, and with the governor in its normal position will rotate the lever H in or out, as the case may be, until the valve stem C⁴ is flush with the cap E. He will then tighten the parts together, knowing that he has set the zero of the governor at such point that the valve 105 will be wide open.

I claim:

1. A valve comprising a valve casing, a 110

- spring controlled plug, a valve operating stem, and a valve piston suspended between said plug and said stem and in contact with said stem.
5. 2. A valve comprising a valve casing, a spring controlled plug a valve operating stem, and a valve piston suspended between said plug and said stem and in contact with said stem and adapted to be operated thereby.
10. 3. A valve comprising a valve casing, a plug, a valve piston within said casing, an extension upon said valve piston lying within said plug, a spring within said plug and in contact with said extension, a valve operating stem separate from but in contact with said valve piston, said plug movable to adjust the setting of said valve.
15. 4. A valve comprising a valve casing a valve piston therein an upper extension from said piston having a lateral enlargement, a hollow plug surrounding said extension and in contact with said enlargement a spring within said plug and adapted to bear against said plug and said enlargement, a valve operating stem in contact with but separate from said valve piston.
20. 5. A valve comprising a valve casing a valve piston therein an upper extension from said piston having a lateral enlargement, a hollow plug surrounding said extension in contact with said enlargement a spring within said plug and adapted to bear against said plug and said enlargement a valve operating stem in contact with but separate from said valve piston and adapted to move said piston in opposition to said spring.
25. 6. A valve comprising a valve casing, inlet and outlet ports, a hollow plug in one end of said casing a valve piston in said casing, an extension from said valve piston within said plug a hole in the end of said plug through which said piston extension penetrates and by means of which the position of said valve piston may be observed.
30. 7. A valve comprising a casing, a hollow plug adjustable in one end of said casing a valve piston within said casing an extension from said valve piston lying within said plug, a lateral enlargement on said extension in contact with the interior of said plug, a spring within said plug in contact at one end with said plug and at the other with said enlargement a hole in said plug through which said extension penetrates and by means of which the position of said valve body may be observed.
35. 8. A steam valve comprising a casing having inlet and outlet ports, one end of said casing being closed a valve piston in said casing and adapted to close said outlet ports, said valve piston perforated to permit the passage of steam therethrough, and a valve operating stem in contact with but unconnected with said valve piston.
40. 9. A steam valve comprising a casing having inlet and outlet ports one end of said casing being closed a valve piston in said casing and adapted to close said outlet ports said valve piston perforated to permit the passage of steam therethrough a valve operating stem in contact with but separate from said valve piston and a bushing in the lower end of said valve casing surrounding said stem the surface on the upper end of said bushing inclined away from said stem.
45. 10. A steam valve comprising a casing having inlet and outlet ports one end of said casing being closed a valve piston in said casing and adapted to close said outlet ports said valve piston perforated to permit the passage of steam therethrough a valve operating stem in contact with but separate from said valve piston and a bushing in the lower end of said valve casing surrounding said stem, the surface on the upper end of said bushing inclined away from said stem and said end being smaller than the interior of the valve casing.
50. 11. In a fluid engine a governor valve, a socket enclosing the valve an indicator associated with the valve, and visible from without the socket for indicating the position of the valve, and an adjustable governing connection for the valve, where the operator may with reference to the indicator set the valve at the initial position.
55. 12. In a fluid engine, a valve casing, a valve reciprocating therein, an adjustable governing connection adapted to exert a governing impulse thereagainst, the stem of the valve being adapted to project through the wall of the casing and serve as an indication of the position of said valve.
60. 13. In a fluid engine, a valve casing, a valve reciprocating therein, an adjustable governing connection for the valve, the stem of the valve being adapted to project through the wall of the casing and serve as an indication of the position of said valve.
65. Signed at Chicago county of Cook and State of Illinois, this 30th day of August, 1920.

CHARLES W. DAKE.
